(57) **CLAIM**

We claim the ornamental design for a kettle, as shown and described.

DESCRIPTION

FIG. 1 is a front perspective view of a kettle showing our new design;

FIG. 2 is a right side view thereof;

FIG. 3 is a left side view thereof;

FIG. 4 is a front view thereof;

FIG. 5 is a rear view thereof;

FIG. 6 is a top plan view thereof; and,

FIG. 7 is a bottom plan view thereof.

The features shown in broken lines depict environmental

subject matter only and form no part of the claimed design.
